EASEL

Bernt Anker Hoffmann, Oslo, Norway

Application April 29, 1946, Serial No. 665,773
In Norway January 28, 1944

Section 1, Public Law 690, August 8, 1946
Patent expires January 28, 1964

4 Claims. (Cl. 248—197)

1

The present invention has to do with certain improvements in easels, and especially in field or portable easels intended to be used for painting in open air.

It is an object of this invention to provide a foldable easel, especially for out-of-door work, which is so constructed that a still not dry picture may be transported sitting in the easel without damage of the painting or any risk for soiling the painter's dress by the wet paint.

A further object of the invention is to provide a picture protecting screen or shutter which when in non-protecting position may serve other useful purposes such as serving as a shelf upon which the artist conveniently places his utensils, such as palette, colour-tubes etc.

Another object of the invention is to provide a protecting shutter of the type indicated, which is of very simple construction and easy to operate.

The various features of my invention will be fully understood from the following detailed description with reference to the accompanying drawing, in which:

Figure 1 is a front view of the easel in erected condition.

Figure 2 is a side view thereof and Figure 3 is a rear view of the same, the legs being partially collapsed.

Figure 4 is part of a rear view of the easel on a larger scale.

Figure 5 illustrates a section on the line V—V in Fig. 4.

Figure 6 is a front view of the easel in entirely collapsed condition.

Figures 6a and 7 illustrate details on a larger scale, and

Figure 8 is a view on a larger scale, of a further embodiment of the connection of the slidable legs of the easel.

On the drawing 1 indicates the outer frame of the easel, the rear side of which is strengthened by inclined stays 9, 9'. To the lower part of the two side members of the frame are by means of threaded bolts and thumb nuts 3, 3' pivotally secured the topmost members 2, 2' of two parallel legs, the lower portions of which consist of slidable links 4, 4' and 5, 5' respectively, which may also be swung on threaded bolts 6, 6' and 7, 7' respectively, provided with thumb nuts. These bolts pass through longitudinal slots in the links 4, 4' and 5, 5', so that such links may be slided longitudinally as well as pivoted and also secured into the desired position by means of the thumb nuts. The links 2 and 2' are preferably inter-

2

connected by means of a cross bar and stays 8, 8', so that they always remain parallel. The legs comprising the links 2, 2', 4, 4' and 5, 5' constitute the front legs of the easel.

5 The easel has a single rear leg, consisting of links 10, 11 and 12. The topmost end of the link 10 is by means of a hinge 15 articulated to the top member of the frame 1, so that the rear leg as a whole may be tilted in a plane at right angles to the frame 1. The middle link 11 of the rear leg is secured to the link 10 by means of a threaded bolt with thumb nut 13 and is slidably and pivotally connected with the link 12 by means of a threaded bolt 14, which passes through a longitudinal slot 16 in the link 11 and is provided with a thumb nut. To the link 12 is secured a cross member 20 which forms a carrying grip for the easel in collapsed condition therof. Between its ends the top link 10 has secured thereon to a hinge 18 carrying an arm 17 which, when the rear leg has been swung rearwardly as shown in Fig. 2, is swung forwardly to rest against the back of the frame in the position shown in full lines in said figure, in order to keep the rear leg at a certain angle distance from the frame. When the easel is collapsed the arm 17 is swung on to the link 10, as indicated in dotted lines, and is secured in this position by means of a hook 19. When the top link 10 is swung on to the frame 1 it is secured in such position by means of a locking arm 29, which is pivotable on a pin 30 on one cross bar 23 of the frame, so that said arm may be swung across the link. The locking arm is secured in such position by sliding a notch near one end thereof under a screw head 31 or the like. When the link 10 is to be swung rearwardly on the hinge 15, the link is first unlocked by swinging the locking arm to a position parallel to the other cross bar 23'.

40 The blind frame 22 of the picture, with its canvas 21 secured thereto, is placed in the frame 1 resting against the cross members 23 and 23' thereof. The blind frame is secured in such position by means of four angular clamps 26, which 45 grasp over the blind frame and are secured to the frame cross bars 23, 23' by means of threaded bolts 25 and thumb nuts thereon. Said bolts 25 pass through longitudinal slots 24 in the cross bars, so that the clamps 26 may be shifted in the longitudinal directions of said cross bars and be secured in desired position in accordance with the dimensions of the blind frame.

45 For protection of the picture during transport the frame 1 is at its front side provided with a 50 swingable screen or shutter. The same consists

of two halves 32 and 33 respectively interconnected by hinges 34. The lowermost edge of the lower half member is articulated to the frame 1 by means of hinges 31'. Each screen half consists of a frame 43 with cross bars 38, on to which 5 is tied a suitable fabric, such as canvas or the like 37.

For transport of the easel the screen halves 32 and 33 are swung upwardly to a position indicated by dotted lines in Fig. 2, in which they cover the front of the picture and the frame 1. To provide for a sufficient distance between the screen and the picture in such position each edge member of the frame 1 is between its ends provided with a raised portion 36, for instance with a wooden block secured thereto, against which the abutting edges of the screen halves may rest. The screen is locked in such position by means of locking pins 45 turnable in each block 35 and having their free ends bent at an angle. Each locking pin enters a corresponding slot 44 in the screen frame 43 when the latter is placed in the screening position, and the locking is obtained by turning each pin 45 so that its angular part takes a position across to the slot, as plainly shown in Fig. 6a. The turning of each pin into a position in which its angular part is parallel to the corresponding slot 44 will unlock the screen.

By means of lines or chains 36 the screen is connected to the side members of the frame 1. Therefore, when the screen is turned down to the position shown by full lines in Fig. 2, a shelf is formed upon which the artist may place his palette, colour tubes etc. In order that said shelf shall not become too wide the halves 32 and 33 are thereby folded together on their interconnecting hinges 34 so that they overlap each other. The lines 36 are suitably secured to the member 33 near to the hinges 34, so that during the downward swinging a momentum comes into existence, causing the half 33 to swing inwardly towards the frame 1.

The adjacent parts of the pivotable leg members and also the corresponding parts of the front leg links 2, 2' and the frame 1 respectively are, as shown in Fig. 7, provided with cooperating knots 39, for instance screw heads, and recesses 40, in order to further prevent undesired swinging movement of the leg links after the thumb nuts having been tightened.

The constructive details may vary within the scope of the invention. Thus, as illustrated in Fig. 8, the slideable leg members may be interconnected by means of tongue and groove instead of slots and screws.

In operation the easel takes the position illustrated in Figs. 1 and 2. For transport it is collapsed in the following manner.

First the face of the picture is screened off by raising the screen halves 32 and 33 to the top-most position indicated by dotted lines in Fig. 2. Figure 6 includes a front view of the screen in such position. The screen is locked by turning the locking pins 45. Then the thumb nuts 13 and 14 are untightened and the links 11 and 12 of the rear leg are pivoted and eventually slid together so that they overlap the link 10, whereupon the nuts are tightened. The distance arm 17 is raised to the position shown by dotted lines and the rear leg, now shortened as above described, is swung on its hinge 15 on to the rear side of the frame 1.

and locked by means of the locking arm 29, as shown in Figs. 3 and 4. Then the easel's front legs are collapsed. The thumb nuts 6, 6' and 7, 7' are untightened, whereupon the links 4, 4' and 5, 5' are pivoted and displaced to the positions shown in Fig. 3 and then secured by tightening the nuts. Nuts 3, 3' are released; the links 2, 2' and the links 4, 4' and 5, 5' connected therewith are swung somewhat more than 180° rearwardly and upwardly into positions at each side of the frame 1, whereupon the nuts 3 and 3' are tightened. The easel now is in entirely collapsed condition, as illustrated in Fig. 6, and may be carried by means of the grip 20.

To erect the easel the above described operations are effected in inverse sequence.

Having now particularly described and ascertained the nature of my said invention and in what manner the same is to be performed, I declare that what I claim is:

1. An easel including a picture-supporting structure adapted to encase a picture, a protective screen pivotally attached at the bottom of said structure, said screen comprising a pair of articulated sections, means for supporting said sections in overlapping, superimposed relationship at the bottom of the structure and means for releasably locking said sections in extended position over a picture supported by and disposed within the structure.

2. An easel according to claim 1 in which the means supporting the sections in overlapping position is connected to the upper section adjacent the line of articulation so as to cause the sections to overlap as they fall to the horizontal position.

3. An easel comprising a picture-carrying frame adapted to encase a picture, a screen pivotally attached at the bottom of the frame and adapted to be swung upwardly into protective position in front of the carrying frame, means spacing said screen from said carrying frame and means for releasably locking the screen in protecting position, said screen being articulated transversely and said locking means acting on the upper section of the screen.

4. An easel including a picture-supporting structure adapted to encase a picture, a screen provided with a slot and pivotally attached to said structure at the lower edge thereof and adapted to be swung upwardly into a protecting position in front of a picture disposed within the supporting structure and means for releasably locking said screen in said protecting position, said means comprising an angular locking pin pivotally secured to the supporting structure and registering with the slot provided in said screen.

BERNT ANKER HOFFMANN.
